UNITED STATES PATENT OFFICE.

ATTILIO WM. FORCHIELLI, OF PHILADELPHIA, PENNSYLVANIA.

BANJO ATTACHMENT.

Application filed September 15, 1923. Serial No. 662,902.

This invention relates to musical instruments and more particularly to an amplifier for attachment to banjos.

The approved type of banjo amplifiers now in use are designed in such manner that the amplifier must be removed to permit adjustment of the tension hoop rods of the banjo head which is inconvenient, tedious and time absorbing especially where different adjustments of the head are desired during the rendering of an orchestral program.

It is an object of the present invention to provide an amplifier construction which will permit adjustment of the tension hoop rods without requiring detachment in any manner with the operation of efficiency of the amplifier.

Another object is to provide a device so constructed and so related to the banjo that the tension rods employed for tightening or tensioning the head of the banjo may also be employed for securing the amplifier in operative position.

Further objects will appear from the detail description.

In the drawings:—

Figure 1—is a side elevation of the banjo with the amplifier in section attached.

Figure 2—is a top plan view of the amplifier per se partly in section.

The device is intended to be used in connection with a banjo of standard construction which includes an annular rim *a* over which is stretched a head *b*, the peripheral portion of this head being wrapped about a flesh rim, not shown, which fits snugly about rim *a*. A straining or tensioning hoop *d* fits about rim *a* and above the flesh-ring so that by forcing this hoop downwardly about the rim, by means of straining or tensioning rods *e* provided at their upper elements with hooks *e'* which engage over hoop *d* the head *b* can be tensioned or stretched to the desired extent. The banjo constructed in this manner is of standard construction and forms no part of my invention except in so far as it co-operates with means to be described to accomplish the desired result.

The attachment, which may be termed a deflector or amplifier in that it acts to deflect the sound upwardly from beneath the banjo head, includes a disc 1 which is preferably of concavo-convex cross section and is provided with an upwardly extending pe-

ripheral flange or wall 2. A plurality of 55 equally spaced bosses or lugs 3 project inwardly from wall 2 and each boss is formed adjacent to its lower end with an inwardly projecting shoulder 4, these shoulders provide seats for reception of the lower portion 60 of rim *a* of the banjo. Each of the lugs 3 is provided with a bore 5 and with a recess 6 concentric with the bore but of greater diameter, this recess extending from the lower face of disc 1. In applying the device or 65 attachment the shanks of rods *e* are inserted through bores 5 of lugs 3 and suitable nuts *f* such as are commonly employed on banjos are threaded on to the lower ends of these shanks, these nuts being positioned within 70 recesses 6. For this purpose, a key of a known type is employed, this key being adapted to fit into recesses 6 and about the nut *f*. This provides very simple and efficient means for securing the device in place 75 while permitting ready adjustment or tensioning of the head of the banjo without any necessity for removing the attachment or other parts.

From the foregoing description taken in 80 connection with the accompanying drawings it will be noted that, when the attachment is in place the tension rods can be adjusted as quickly and easily as if there were no attachment on the banjo, which is of great 85 practical importance. As an additional feature, it will be noted that, when the attachment is in place, the nuts *f*—and the lower portions or ends of the shanks of tension rods *e* are positioned within recesses 6 so 90 that there are no projections such as would tend to catch in the player's clothing. This provides a device of extremely simple construction and high efficiency which may be quickly and easily applied to banjos of 95 standard construction without necessitating any change whatever in the construction of the banjo itself.

What I claim is:—

The combination with a banjo including a 100 rim, of an amplifier formed of a single piece of material and having a concavo-convex circular bottom with the concave side facing the banjo, an upstanding circular rim formed about said bottom and having a plurality of circumferentially spaced lugs formed thereon and extending inwardly, said lugs being spaced to provide sound es-

caping spaces, shoulders formed on the inner sides of said lugs, the rim of said banjo resting upon said shoulders and against the adjacent faces of the lugs, whereby sound space 5 will be provided beneath the banjo and escape of the sound will be permitted through the spaces formed by the lugs, said lugs be-

ing provided with clamping bolt receiving openings, and with countersinks extending upwardly from the bottom of the amplifier 10 for receiving the clamping nuts.

In testimony whereof I affix my signature.

ATTILIO WM. FORCHIELLI.
